UNITED STATES PATENT OFFICE.

WILLIAM MILES BROWN, OF CROOKSTON, MINNESOTA.

EXCAVATING-MACHINE.

No. 900,659.

Specification of Letters Patent.

Patented Oct. 6, 1908.

Application filed July 23, 1907. Serial No. 385,168.

To all whom it may concern:

Be it known that I, WILLIAM MILES BROWN, a citizen of the United States, residing at Crookston, in the county of Polk 5 and State of Minnesota, have invented new and useful Improvements in Excavating-Machines, of which the following is a specification.

This invention relates to ditching and excavating machines adapted to be used for digging or excavating ditches, drainage canals, and irrigation ditches and the like; and it has for its object to simplify and improve the construction and operation of this 15 class of devices; to provide a machine of simple construction which shall be operable in two directions so that it will not be necessary to turn the machine at the end of the excavation; to provide a machine in which 20 the dirt that is being excavated may be conveniently discharged at either side of the excavation and at a suitable distance therefrom; to provide an improved structure in which the excavating member shall be 25 movable laterally of the frame of the machine, so that an excavation of considerable width may be made without re-setting or readjusting the machine; and to construct a machine of the character described which 30 shall possess superior advantage in point of simplicity, durability and general efficiency.

With these and other ends in view which will readily appear as the nature of the invention is better understood, the same consists in the improved construction and novel arrangement and combination of parts which will be hereinafter fully described and particularly pointed out in the claims.

In the accompanying drawings has been 40 illustrated a simple and preferred form of the invention; it being, however, understood that no limitation is necessarily made to the precise structural details therein exhibited, but that changes, alterations and modifications within the scope of the invention may be resorted to when desired.

In the drawings, Figure 1 is a top plan view of a portion of an excavating machine constructed in accordance with the invention. 50 Fig. 2 is a longitudinal vertical sectional view taken on the plane indicated by the line 2-2 in Fig. 1. Fig. 3 is a transverse sectional view taken on the plane indicated by the line 3-3 in Fig. 2. Fig. 4 is a vertical transverse sectional view taken on the plane 55 indicated by the line 4-4 in Fig. 2. Fig. 5 is

a detail plan view of the laterally adjustable frame which serves to support the scoop frame and related parts. Fig. 6 is a vertical sectional view taken on the plane indicated by the line 6-6 in Fig. 5. Fig. 7 is a diagrammatic view showing the machine in position for operation.

Corresponding parts in the several figures are denoted by like characters of reference. 65

The two ends of the improved machine are practically of identical construction; and in Figs. 1 and 2 of the drawings the central portion and one end of the machine, only, has been shown, for the purpose of showing the 70 parts on a larger scale than would otherwise be possible; it being understood that the end of the machine which does not appear in these views is a duplication of the end which is shown. 75

The main frame A of the improved machine is preferably built of structural iron; it being composed of beams or bars of any suitable cross-section to insure the necessary qualities of lightness and strength; said bars or beams 80 being assembled in any convenient manner to form a frame structure of the desired dimensions; the main frame being substantially rectangular in shape, and supported at the ends thereof in trucks, one of which is 85 shown at B; said truck including the wheels 1, axle 2 and bolster 3; the latter being mounted pivotally beneath the frame upon a king bolt 4 which is equipped with a pinion 5 meshing with a pinion 6 upon a steering rod 7 90 having a hand wheel 8 by means of which it may be manipulated to steer the machine.

The main frame A supports at its center an auxiliary frame C including posts or uprights 9. This auxiliary frame supports a main 95 shaft 10 which extends transversely across the main frame and which is of non-circular cross-section for the greater portion of its length, as will be clearly seen by reference to Fig. 2 where a shaft of square cross-section 100 has been shown. Slidably mounted upon the shaft 10 is a main driving pulley 11, which latter is preferably grooved for the accommodation of a chain, cable or other flexible element which may be wound at least 105 once around said pulley.

Suitably supported in brackets 12 that depend from the sides of the main frame, adjacent to the auxiliary frame C, are transverse shafts one of which is shown at 13; 110 a slidably supported upon said shaft 13 is a frame D including the beams or side members

14, the outer ends of which are secured upon and connected by a plate 15 carrying a suitably constructed scoop 16 having a sharp edge 17 adapted for engagement with the 5 soil that is to be excavated.

18 is an elevator frame or trough, the upper end of which is slidably mounted upon a transverse shaft 19 of square or non-circular cross-section; the lower end of said frame or 10 trough being loosely supported upon the plate 15 adjacent to the scoop 16. The frame or trough 18 supports an endless carrier 20 of suitable construction; said carrier being mounted upon rollers 21 and 22, the 15 former of which slidably engages the shaft 19, while the latter is mounted upon a shaft 23 near the lower end of the frame 18.

The main frame A includes transversely disposed channel bars 24, said channel bars 20 being disposed in pairs above the lower end of the frame D; said channel bars serve to support a laterally slideable frame E wherein is journaled a transverse shaft 25 having grooved wheels or pulleys 26 upon which are 25 wound chains or flexible elements 27, the free extremities of which are made fast to the frame D, near the free end of the latter. The shaft 25 carries a worm gear 28 meshing with a worm 29 upon a shaft 30 which is suitably 30 supported for rotation in the frame E and carries at its upper end a hand wheel 31 whereby it may be manipulated to effect rotation of the shaft 25, thereby winding or unwinding the flexible elements 27 and raising 35 or lowering the free end of the frame D, as may be desired. The frame E also carries an upright shaft 32 having a hand wheel 33 and secured upon said shaft, and wound several times thereon are the inner ends of chains 40 or flexible elements 34, the opposite ends of which are made fast to the sides of the main frame A; thus it will be seen that by rotating the shaft 32, so as to wind one and unwind the other of the chains 34, the frame E may be 45 moved transversely of the frame A, thus effecting lateral adjustment of the end of the frame D with which the said frame E is connected by means of the flexible elements 27.

For the purpose of effecting lateral adjustment of the upper end of the frame D there is provided an upright shaft 35, supported for rotation in suitable bearings upon the frame A and provided with a hand wheel 36. Suitably secured to the shaft 35 are the ends 55 of a pair of chains or flexible elements 37, said flexible elements being guided over suitably supported pulleys 38 and connected with the opposite sides of the frame D, near the upper end of said frame. For the purpose of effecting lateral adjustment of said frame D the shafts 32 and 35 are preferably rotated simultaneously and in unison, thus causing the said frame D to slide or move upon the supporting shaft 13, the elevator 60 trough or frame 18 sliding in like manner

upon the transverse shaft 19, until the desired adjustment has been effected. By this construction a scoop of suitable width may be mounted in a supporting frame of a width greatly exceeding that of said scoop, and the 70 latter may be adjusted to make an excavation of any desired width within the limits of the width of the supporting frame in two or more operations, thus enabling a machine, capable of making an excavation of large dimensions 75 to be operated successfully with comparatively light motive power. It is obvious that no limitation is made to the dimensions or proportions shown in the accompanying drawings, but that the supporting frame may 80 be made, relatively of much greater width, thus enabling a correspondingly wider excavation to be made by the machine.

Supported in suitable bearings below and parallel to the main shaft 10 is a shaft 39 85 which receives motion from said main shaft 10 through the medium of a chain 40 engaging sprocket wheels upon the said shafts. Mounted upon the shaft 39 is a sprocket wheel 41 from which motion is transmitted 90 by a link belt 42 to a sprocket wheel 43 upon the shaft 19 which supports the upper end of the carrier trough 18 and of the endless carrier mounted in said trough.

Suitably supported transversely of the 95 main frame A is an endless carrier 44; said carrier being arranged beneath the discharge ends of the carriers 20 in the troughs or frames 18 extending towards the two ends of the main frame A. The carrier 44 is mounted 100 upon rollers 45 upon longitudinal shafts 46; the means for driving the endless carrier 44 will be presently described.

The sides of the frame A are provided with laterally extending lugs or brackets 47 supporting shafts 48 upon which the carrier frames 49 are hingedly mounted; said frames are provided near their outer ends with shafts 50 which serve, in conjunction with the shafts 48, to support endless carriers 51 of 105 suitable dimensions. Pivotedly supported upon the shaft 48, adjacent to the lugs or brackets 47, are brace rods 52 which converge outwardly to form V-shaped frames F, the apices of which are connected with the 110 sides of the carrier frames 49 by means of chains or flexible elements 53. Additional chains or flexible elements 54 connect the apices of the frames F with shafts 55 that are supported for rotation in the auxiliary frame 115 C, said shafts 55 constituting drums upon which the flexible elements 54 may be wound for the purpose of elevating the outer or free ends of the carrier frame 49. The drums or shafts 55 may be operated in any suitable 120 manner; in the drawings, there have been shown additional shafts 56, supported parallel to the shafts 55 and having pinions 57 meshing with pinions 58 upon the shaft 55. The shafts 56 are provided with hand wheels 125

59 whereby they may be rotated for the purpose of rotating the shafts 55 to wind or unwind the flexible elements 54, as may be desired, for the purpose of effecting the desired 5 adjustment of the carrier frames 49. Suitable well known means of any kind may be used for the purpose of retaining the shafts 55 at various adjustments, or for the purpose of checking their rotation; but such means 10 are well known in this class of mechanism and have not been illustrated.

Countershafts 60 are supported for rotation in the auxiliary frame C above and adjacent to the shafts 55, and said countershafts are 15 provided with bevel pinions 61 meshing with bevel pinions 62 upon the main shaft 10, from which motion will thus be transmitted to the countershafts 60. One of the latter carries a sprocket wheel 63 which is connected by a link belt 64 with a sprocket wheel 65 upon one of the shafts 46 supporting the transversely disposed endless carrier 44, which will thus be driven.

Suitably secured upon the sides of the main 25 frame A, adjacent to the endless carrier 44 are aprons 66 overhanging the carriers 51 supported by the frames 49 for the purpose of guiding material from the said carrier 44 onto either one of the carriers 51, as will be 30 readily understood.

In operation the improved machine is intended to run in the ditch or excavation that is to be made, the machine being obviously made of suitable dimensions, especially as to 35 width, to make an excavation of a desired size.

The machine may be propelled by power supplied by two stationary engines, one at either end of the work, the power being transmitted by means of a chain or cable one end of which is attached to a short tongue or draft member at the end of the excavator, the other end being attached to a drum or capstan device on the engine.

45 The elevators may be driven by a wire cable, W, passing around the pulley 11 upon the shaft 10 of the machine, the ends of said cable being anchored or made fast in any suitable manner adjacent to the end of the 50 path of the excavating machine, or the elevators may be driven by a gasolene, steam or other motor supported upon the main frame of the machine, said motor being utilized for transmitting motion through any suitable 55 intermediate mechanism of the shaft 10 carrying the pulley 11. It will be understood, however, that no limitation is intended to be made to these or to any other particular methods of operating the machine 60 to propel the same or to supply motive power to the live parts of the machine. Under some circumstances it may be desirable to construct a machine operable in one direction only but involving in its structure the 65 principles herein shown and described; a ma-

chine of such structure, which will be comparatively light, may be propelled by animal power, and it is to be understood that I reserve the right to these and other modifications involving only mechanical skill in their 70 execution.

When the machine is propelled, the scoop disposed at the forward end of the frame and which has been previously adjusted to the desired position, engages the soil which is 75 conveyed over the scoop onto the endless carrier 20 where it is conveyed to the transversely disposed carrier 44, which latter discharges onto the carrier 51 at either side of the frame, thus causing the dirt to be discharged at the side of the ditch, and at any desired distance from the excavation. The dirt may obviously be discharged into the boxes of dump wagons or other receptacles, if desired, or it may be dumped at the side of 85 the ditch.

The machine may, as previously stated, be operated by a stationary engine, and when this is the case it will obviously make a trip or a length which is governed by the amount of 90 available power, and by the length of flexible connections that are being utilized; when the end of the excavation or the end of the trip is reached, the movement is reversed; it being obvious that the scoop frame which is 95 temporarily at the rear end of the machine will be raised to a position where it will not interfere with the progress of the machine.

The scoop carrying frame D may be readily adjusted by the means provided for the purpose, as hereinbefore described, and it is obvious that the lower or free end of the frame 18 supporting the carrier 20, which rests loosely upon the frame D will be adjusted with the latter.

The improved machine is simple in construction, and thoroughly efficient for the purposes for which it is provided.

Having thus fully described the invention, what is claimed as new is:

1. In an excavating machine, a wheel supported traveling frame, shafts supported transversely in said frame, a scoop carrying frame laterally slidable upon one of said shafts, a carrier frame slidably supported 115 upon the other shaft and loosely supported at its free end upon the scoop carrying frame, means for effecting lateral adjustment of the scoop carrying frame, and means for effecting rotation of the shaft supporting the carrier frame.

2. In an excavating machine, a wheel supported traveling frame, shafts supported transversely in said frame, a laterally adjustable scoop carrying frame slidable upon 125 one of said shafts, a transversely adjustable carrier frame slidable upon the other shaft, an adjusting frame supported in the traveling frame for transverse slidable movement, a drum carrying shaft supported for rota- 130

tion in the adjusting frame, flexible elements connecting the said shaft with the free end of the scoop carrying frame, means for effecting transverse adjustment of the latter, and 5 a hand operated shaft carrying a worm gear for effecting rotation of the shaft supporting the carrier frame.

3. In an excavating machine, a wheel supported traveling frame, laterally adjustable 10 scoop carrying frames supported therein, carrier troughs having free ends supported by the scoop carrying frames and adjusted with the latter, a transversely disposed endless carrier arranged intermediate the carrier 15 troughs to receive material discharged from the latter, laterally extending endless carriers supported beneath and adjacent to the transversely disposed endless carrier, and means for operating the several carriers.
- 20 4. In an excavating machine, a wheel supported traveling frame having transversely disposed shafts and transversely disposed channel bars, an adjusting frame slidably supported by the channel bars, a scoop carrying 25 frame slidably supported upon one of the transverse shafts, a carrier frame slidably supported upon another transverse shaft and having a free end supported upon the trough carrying frame, a drum carrying shaft supported for rotation in the adjusting frame, 30 flexible elements connecting said shaft with the free end of the scoop carrying frame, a worm gear upon the drum carrying shaft, an adjusting shaft having a worm meshing 35 with said gear, means for effecting transverse adjustment of the adjusting frame, means for effecting transverse adjustment of the scoop carrying frame, and means for rotating the shaft supporting the carrier frame.
- 40 5. In an excavating machine, a wheel supported traveling frame having laterally extending lugs or brackets, shafts supported for rotation in said brackets, carrier frames pivoted upon said shafts, endless carriers 45 supported in said frames, supporting bars pivoted upon the lugs or brackets and converging to form V-shaped frames, flexible elements connecting the apices of said frames with the carrier frames, shafts supported for 50 rotation upon the traveling frame, and flexible elements connecting said shafts with the apices of the V-shaped frames.
6. In an excavating machine, a wheel supported traveling frame, an auxiliary frame 55 supported thereon, transversely slidable scoop carrying frames, transversely slidable

carrier frames having free ends supported upon the scoop carrying frames, endless carriers in the said frames, a transversely disposed endless carrier supported beneath the 60 discharge ends of said endless carriers, laterally extending endless carriers supported beneath and adjacent to the transversely disposed endless carrier, a transversely disposed main shaft having a chain wheel, and means 65 for transmitting motion from said main shaft to the several carriers of the machine.

7. In an excavating machine, a wheel supported traveling frame having transversely disposed shafts and transversely disposed 70 channel bars, a laterally slidable frame supported by the channel bars, a scoop carrying frame slidably supported upon one of the transverse shafts, an elevator frame slidably supported upon a nut and transverse shaft 75 and having its free end supported upon the scoop carrying frame, a drum carrying shaft supported for rotation in the laterally slid- 80 able frame, flexible elements connecting said shaft with the free end of the scoop carrying frame, a worm gear upon the drum carrying shaft, an adjusting shaft having a worm meshing 85 with said gear, means for effecting transverse adjustment of the laterally slidable frame, means for effecting transverse ad- 90 justment of the scoop carrying frame, means for rotating the shaft supporting the elevator frame, and means carried by the shafts for affecting the desired adjustment of the latter mentioned frame.

8. In an excavating machine, a wheel supported traveling frame having depending hangers or brackets, a transverse shaft supported by said hangers, a scoop carrying frame slidably supported upon said shaft, an 95 adjusting frame supported in the traveling frame for transverse slidable movement, upright shafts carried by the traveling frame and the adjusting frame and provided with hand wheels, said upright shafts having 100 chains wound thereon, said chains being connected to the sides of the wheel supporting frame and to the sides of the scoop carrying frame for effecting lateral adjustment of said 105 scoop carrying frame.

In testimony whereof, I affix my signature in presence of two witnesses.

WILLIAM MILES BROWN.
